UNITED STATES PATENT OFFICE.

ALBERT F. F. GILSON, OF NORWOOD, NEW JERSEY, ASSIGNOR TO WESTERN ELECTRIC COMPANY, INCORPORATED, OF NEW YORK, N. Y., A CORPORATION OF NEW YORK.

HEAD SET.

Application filed December 26, 1919. Serial No. 347,517.

To all whom it may concern:

Be it known that I, ALBERT F. F. GILSON, a citizen of the United States, residing at Norwood, in the county of Bergen, State of New Jersey, have invented certain new and useful Improvements in Head Sets, of which the following is a full, clear, concise, and exact description.

This invention relates generally to telephone head sets and particularly to an improved form of support for the receiving instruments.

It has been the practice in making up devices of this general nature to mount the receivers in relatively permanent relation on the supporting head gear employed. This arrangement has not been wholly satisfactory in that it gave rise to difficulty in making a change of receivers for any purpose and in adjusting the receivers in the position best adapted for use by the individual operator. This has been particularly the case with head sets such as have been used by aviators wherein the emergencies and exigencies of flying frequently require a hurried exchange of instruments and always require the best possible adjustment of the ear pieces to the head of the user. The objects of the invention are to overcome the objections referred to and to provide readily detachable and adjustable supporting means for holding the receivers in position in the head gear.

The invention consists in mounting the receivers on a suitable head gear by means of readily separable fasteners, so as to provide for making a rapid removal, interchange or replacement of instruments with a minimum of trouble and without the use of tools of any description. The parts of the head gear which directly support the receivers preferably take the form of adjustable elastic straps which, in combination with flexible seats for the receivers and an arrangement of the fasteners that provide for changes in the relative position of the receivers on their seats, produces an effective means for securing any desired degree of closeness of adjustment of the receivers to the ears of the operator.

In the drawing, Figure 1, is a view in perspective of a telephone head set embodying a preferred form of the invention; and Figure 2 is a similar view on an enlarged

scale of a receiver, showing in detail the means for attaching it to its seat.

Referring to the drawing, there is shown in Figure 1 an instrument-supporting head harness in which a broad leather band or skull-cap member 1 is arranged to fit closely the median line of the head of the wearer from the base of the skull to the forehead, and act as the main supporting member for two elastic bands 2 and 3 with which the cap member 1 is equipped. Suitable loops 4 and 5 serve to attach the elastic bands 2 and 3 to the cap member 1 and provide a longitudinal sliding movement of the band therethrough for adjusting purposes. It will be seen that the elastic bands 2 and 3 are arranged to cross each other substantially at right angles at points adjacent the ears of the wearer, and at the points of intersection receiver-supporting or seat members 6 are provided, which are preferably formed of flexible material such as fabric or leather.

The seat members 6 have the general form of a disc and are stitched or otherwise permanently attached to the oppositely disposed points of intersection of the bands 2 and 3. Formed to co-operatively engage the seat members 6 are similar disc-shaped members 7 carried by the bases of the soft rubber cup members 8 in which the receiving instruments 9, surrounded by inner cup members 10 of sponge rubber, are mounted and shielded from extraneous noise.

In order to provide for a secure and, at the same time, easily disconnected supporting engagement of the disc members 7 carried by the cup members 8 and the seat members 6 carried by the head bands, the complementary parts 11 and 12 of readily-separable fastening members, such as a well-known type of glove fastener, are mounted on the respective disk members in position to be brought into mutual interlocking engagement in the manner shown in Figure 2 of the drawing. Preferably as many as four sets of fasteners are mounted along the margins of the disc members in the manner indicated, and a greater number may be used if desired. It will be seen that not only are easily and quickly detachable means thus provided for securing the receivers in position on the seating members 6, but the relative position or orientation of the receivers

on the seats may be readily varied by turning the cup members 8 through a sufficient angular distance to bring the respective fastener studs 12 into engagement with different respective eyelet members 11, as will be clear.

Not only can the cup members 8 be readily interchanged for repairs or other reasons and adjusted on the seats 6 with equal facility, but by means of the flexible seat member 6, the elastic bands 2 and 3, and the buckles 13 and 14, a snug-fitting adjustment of the receivers to the ears of the user can be obtained, the chin strap 15 assisting materially in providing a firm contact of the forward portions of the cup members with the operator's head, so as to prevent the entrance of rushing air to the interior of the cup.

It will be seen that the head harness 20 shown in Figure 1 is particularly adapted for use under an aviator's helmet, although it is clearly adapted for use in any situation where telephone head sets are employed. By mounting the receivers in a readily detachable position in a head harness separate from the usual helmet, instead of mounting the receivers in fixed positions in pockets formed for the purpose in the walls of the helmet itself, it is possible to use the head harness and receivers without the helmet and, on the other hand, to employ the helmet without the harness and receivers, or merely without one or both receivers, as the operator may desire.

What is claimed is:

35 1. In a telephone head set, a leather skull cap, a woven elastic head harness adjustably

associated therewith, means for supporting a pair of receivers consisting of an outer leather cap and an inner sponge rubber member, fastening means consisting of two part 40 snap fasteners secured symmetrically on two seat members, one of which members is integrally associated with said supporting means, the other of which members is integrally associated with said head harness. 45

2. In a telephone head set, elastic supporting means for a receiving instrument, a seat for the receiving instrument carried by said elastic supporting means, a holder for a receiving instrument, and circularly arranged rows of snap fastener members on said holder and said seat, whereby the position of said holder on said seat may be varied.

3. In a telephone head set, soft pliable 55 leather band supporting means for a receiving instrument, a flexible seat for the receiving instrument carried by said supporting means, and means for securing the receiving instrument to said flexible seat.

4. In a telephone head set, a flexible skull cap adapted to fit the head of the user, an elastic band secured to said cap for supporting a receiver, a flexible seat carried by the elastic band, a flexible cup in which the receiver is supported, and readily detachable means for securing said cup to said flexible seat.

In witness whereof, I hereunto subscribe my name this 23rd day of December, A. 70 D., 1919.

ALBERT F. F. GILSON.
